UNITED STATES PATENT OFFICE.

JOSEPH ANTONUCCIO, OF FRUITVALE, CALIFORNIA.

COMBINATION KITCHEN-BOILER.

1,035,514.

Specification of Letters Patent. Patented Aug. 13, 1912.

Application filed October 25, 1911. Serial No. 656,732.

To all whom it may concern:

Be it known that I, JOSEPH ANTONUCCIO, a citizen of the United States, residing at 3624 Vermont street, Fruitvale, in the county 5 of Alameda and State of California, have invented a new and useful Combination Kitchen-Boiler, of which the following is a specification in such full and clear terms as will enable those skilled in the art to construct and use the same.

This invention relates to a kitchen boiler used for the purpose of heating water by means of a gas burner and heating drum installed within the boiler.

15 It will be understood by those skilled in the art that it is necessary to have as great an area of metal in contact with hot gas from the burner as possible, and to accomplish this object, flues are run through the 20 boiler and a pipe is run from the heating drum through the flue and back into the top of the boiler. This result of the construction gives heating surface—with the interior of the flue and exterior of the 25 water pipe therethrough. Heretofore it has been customary to connect the outlet hot water pipe with the hot water pipe leading from the burner, in which event it is necessary to have the pipe leading into the 30 boiler from the burner very short, in order to prevent the accumulation therein of air and steam. Another disadvantage of this is that the gas burner heats the water in the 35 boiler very unevenly, the top of the boiler being about 200 degrees when the bottom may be 65 degrees.

This invention, therefore, seeks to produce a device which will heat the entire boiler full of water evenly, while at the 40 same time it will permit the escape therefrom of any steam or air which may collect at the top of the boiler.

In the drawings in which the same numeral of reference is applied to the same 45 portion throughout the several views, Figure 1 is a sectional view of the boiler showing the boiler and heating drum in side elevation, and Fig. 2 is a sectional plan view of the boiler showing the location of the 50 several pipes connected therewith.

The numeral 1 represents the boiler shell, in which a conical bottom 2 is secured, a flue 3 extending from the top of said conical bottom through the top of the boiler. A 55 hot water pipe 4 is connected with the top of the boiler, said pipe not extending below

the bottom of the fitting in the boiler shell, into which it is secured, on the opposite side of the boiler from the hot water outlet pipe 4, a cold water inlet pipe 5 is secured into 60 the fitting 6, said cold water pipe extending to a point near the bottom of the boiler. It is to be observed at this point that it is necessary for the cold water pipe to direct its flow of water downwardly in order to prevent the incoming cold water from disturbing the entire mass of water and mixing the cold and hot water unduly.

The boiler is supported by means of a stand 7, said stand having a cross bar 8 for 70 supporting the burner 9, a gas supply pipe 10 is connected to the burner and a valve 11 regulates the supply thereto, a small burner 12 and a valve 13 being used to light the larger burner.

Above the burner 9 there is a heating drum 14, said heating drum being supplied with cold water from a pipe 15, which is connected with the bottom of the boiler at 16, a faucet 17 being used for cleaning the 80 sediment out of the boiler and heating drum. From the top of the drum 14, a pipe 18 extends through the flue 3 and it has suitable connections with a pipe 19, which extends downwardly into the boiler 85 about one half the depth thereof. This pipe may be provided with a plurality of holes if so desired, but it is not absolutely essential.

The operation of the boiler is as follows: 90 Upon being filled with water and upon the burner being started, the water will flow from the bottom of the boiler through the heating drum and up through the pipe 18 and back into the boiler, whereupon it will 95 be mixed with the cold water at a point about midway of the depth of the boiler, thus producing an evenly heated mass of cold water, since as it is discharged from the pipe 19 it will not collect at the top of 100 the boiler as is usually the case where the hot water inlet pipe from the burner and heating drum is discontinued at the top of the boiler. It is also to be noted that the metal of the drum, the metal of the flue 3 105 and the metal of the pipe 18 is all necessary to give the proper heating surface to quickly heat the body of water in the boiler.

It is necessary to extend the pipe 18 entirely through the flue of the boiler in order to obtain the greatest heating effect from the burnt gas passing through said

22
 flue, as well as to locate the connections of said pipe with the boiler in an accessible position. That is, where these connections are made within the flue it is very difficult 5 to put them in place, to say nothing of the fact that the heating effect is lost for such a distance down as the hot water pipe may be connected below the top of the flue.

Having thus described my invention what 10 I claim as new and desire to secure by Letters Patent of the United States, is as follows:

1. In a combination kitchen boiler, a 15 boiler shell having a conical bottom, a flue leading from the top of the conical bottom through the top of the boiler, a water heating drum adjacent said conical bottom, a water supply pipe connected with the boiler, a hot water outlet pipe connected with the 20 top of the boiler, a pipe extending from the bottom of the boiler to the heating drum and another pipe extending from the heating drum entirely through the flue and downwardly into the boiler about one half 25 its depth, as set forth.

2. In a combination kitchen boiler, a 30 boiler shell having a conical bottom, a flue extending through the boiler from the top of said conical bottom, a cold water supply pipe for said boiler leading to a point adjacent the bottom thereof, a hot water outlet pipe connected with the boiler at the top

thereof, a heating drum immediately below the conical bottom, a gas burner for heating said drum, a supply pipe for the heating drum, and an outlet pipe for said drum, said outlet pipe extending entirely through the flue in the boiler and downwardly into said boiler to a point about the middle thereof, said pipe also having a plurality 40 of openings therein, as set forth.

3. In a combination kitchen boiler, a 45 boiler shell, a flue extending through the boiler, a water heating drum below said flue, a supply pipe connected with the bottom of the boiler and the heating drum, a cold water supply pipe extending through the top of the boiler, a hot water outlet pipe for the heating drum extending entirely through the flue and returning into the 50 boiler and a hot water outlet pipe separate from the hot water pipe, leading from the heating drum and connected with the top of the boiler, whereby the hot water may be drawn from the boiler without the accumulation of gas therein, as set forth.

In testimony whereof I have hereunto set my hand this 16th day of October A. D. 1911, in the presence of the two subscribed witnesses.

JOSEPH ANTONUCCIO.
